UNITED STATES PATENT OFFICE.

FRANK HARRY ANDERSON, OF DES MOINES, IOWA.

OIL BURNER.

Application filed December 3, 1923. Serial No. 678,206.

To all whom it may concern:

Be it known that I, FRANK HARRY ANDERSON, a citizen of the United States, and a resident of Des Moines, in the county of Polk and State of Iowa, have invented a certain new and useful Oil Burner, of which the following is a specification.

The object of my invention is to provide an oil burner of simple, durable and inexpensive construction.

More particularly, it is my object to provide such a burner having a casing for a heating chamber provided with a bottom of novel construction.

15 A further object is to provide in such a structure means hereinafter more fully described for properly feeding the fuel and generating a gas for burning.

An additional purpose of my invention is 20 to provide in the bottom structure means for preventing overflow of the furnace or stove.

Still an additional object is to provide a novel burner structure.

With these and other objects in view, my 25 invention consists in the construction, arrangement and combination of the various parts of my device, whereby the objects contemplated are attained, as hereinafter more fully set forth, pointed out in my claims, 30 and illustrated in the accompanying drawings, in which:

Figure 1 shows a vertical, central, sectional view through an oil burning furnace embodying my invention.

35 Figure 2 shows a detail, sectional view taken on the line 2—2 of Figure 1.

Figure 3 is a detail, sectional view taken on the line 3—3 of Figure 1.

40 Figure 4 is a detail, sectional view through a portion of the bottom of the furnace; and

Figure 5 shows a detail, sectional view through a slightly modified form of the bottom.

45 In the drawings herewith, in which one form of my invention is illustrated, I have used the reference numeral 10 to indicate generally the casing of the furnace or stove.

It will, of course, be understood that when the device is used as a furnace, it may be 50 bricked in or an outer additional casing may be employed, as desired.

I provide the furnace or stove with a bottom of some suitable kind.

55 In the form of burner 10 preferred, I provide a bottom 11 made of concrete. Above the concrete bottom 11 is a fire box bottom

12, which may be made of fire clay, as shown for instance in Figures 1 and 4 or as shown at 13 in Figure 5, where the fire box bottom is made of grate iron. 60

Where the casing is made of thin steel, for instance, I preferably line it above the bottom 11 for a substantial distance with fire brick 14.

The casing may be made of any suitable 65 material, cast iron or otherwise, that is adapted for the purpose.

I provide the bottom 12 or 13, as the case may be, in order to protect the concrete bottom 11 from the intense heat within the fire 70 box portion of the casing.

The casing 10 is provided with a door 15 in its side wall to permit ready access to the interior of the furnace or stove.

Mounted in the bottom of the stove is a 75 receptacle or reservoir 16, the lower end of which projects below the bottom 11 and is provided with a screw cap 17 for clean-out purposes.

Connected with the cap 17 by a suitable 80 fitting 18 is an oil supply pipe 19.

Extending upwardly from the upper end of the reservoir or receptacle 16 is a short pipe 19 on which is a T-nipple 20. Screwed into the upper end of the T-nipple at the 85 upper portion of the fire box bottom 12 is a burner nozzle comprising an upwardly projecting tube 21, having at its upper end an annular, downwardly inclined flange 22, which I have called for convenience the 90 spreader flange.

The upper face or surface of the bottom 12 is concave as at 23. The same configuration is found in the modified form of the bottom shown at 13 in Figure 5. 95

Connected with the nipple 20 is a drain pipe 24 extending to a point outside the casing 10. The drain pipe 24 may lead to the sewer or to any suitable receptacle to take care of overflow.

An air supply pipe 25, the size of which is determined by the size of the furnace or stove and by the heating problem involved, enters the casing 10 at the top or any suitable point and has a portion extending downwardly and terminating just above the spreader flange 22. One or more hot air pipes 26 may lead off from the upper portion of the casing 10. Braces 27 may be provided for the pipe 25, if desired. 105

It will, of course, be understood that suit-

able control valves are provided for the fuel and that the pipe 19 is connected with a source of fuel supply.

In the practical use of my improved furnace or stove, the oil, such as kerosene for instance, is supplied through the pipe 19 to the reservoir 16 and will then flow upwardly to the burner nozzle.

A small amount of oil may be ignited in 10 the concave portion 23 of the bottom 12. After it is burned a short time, the conductivity of the bottoms 12 and 11 is such as to cause a gas to be generated, so that when the flow of oil is properly regulated 15 only a gas will be burned.

The air flowing in through the pipe 25 will be directed downwardly against the open end of the nozzle and the spreader flange 22 and the flame will thus be directed downwardly and outwardly.

The flame will thus be properly spread and the gas will burn with an intense heat.

The concrete bottom 11 is protected against overheating and consequent disintegration by the bottom 12 or 13 as the case may be.

The amount of heat generated can, of course, be regulated by controlling the flow of fuel.

In case the fire should go out or in case 30 the fuel should be permitted to flow to the nozzle when the fire is not burning, the furnace or stove will not overflow and be flooded with oil, but the oil will be held 35 by the concave portion 23 and will flow back through the nozzle 21 to the drain pipe 24. The drain pipe 24 is provided

with an upward bend 28, which stands at a height practically flush with the upper discharge end of the nozzle 21 for thus preventing the flooding of the furnace or stove.

It will, of course, be understood that the size of my burner may be varied as may be desired; that the size of the pipe 25 is determined by the number of cubic feet of rooms to be heated; and the size and number of the pipe or pipes 26 is determined by the heating problem.

The device may be readily made in the form of a furnace or to serve as a heating stove. Any material suitable for the purpose may be employed in any of the parts of my improved oil burning furnace or stove structure, and I intend to cover by the claims of my patent any modified forms 55 of structure or use of mechanical equivalents or employment of a variety of material or changes in shape or size, which may be included within the scope of such claims.

I claim as my invention:

In a structure of the kind described, a casing, a bottom therefor, a fire box bottom above said first bottom, having a concave upper surface, a burner nozzle located within such concave portion, to discharge at a point below the periphery thereof, a reservoir below said nozzle and in communication therewith, located substantially below the upper surface of said fire box bottom and below the point of combustion of the burner so as to be free from sufficient heat to disintegrate the fuel, but to be warmed during the operation of the device.

FRANK HARRY ANDERSON.
